GRINDING WHEEL DRESSER

Frank Greiner, Detroit, Mich., and Conrad L. Ott and Ralph E. Price, Waynesboro, Pa., assignors to Landis Tool Company, Waynesboro, Pa., a corporation of Pennsylvania

Application January 8, 1937, Serial No. 119,704

12 Claims. (Cl. 51—165)

Our invention relates to truing devices for grinding machines, and it is an object of same to provide means for truing the grinding wheel and compensating for wear thereon after a work piece has been removed from the machine.

A further object is to provide means operable upon removal of the work from the machine for initiating operation of the truing and compensating mechanisms.

10 A further object is to provide means whereby said truing operation is performed only after a predetermined number of pieces have been removed from the machine.

15 A further object is to provide means for effecting a faster traverse between the truing tool and the wheel in one direction and the slow traverse in the other direction.

Other objects will become apparent as the description proceeds.

20 Figure 1 is a partial front elevation of a machine in which our invention is incorporated.

Figure 2 is an end elevation of the mechanism which carries the dressing tool.

Figure 3 is a partial section along the lines 25 3—3 of Figure 2.

Figure 4 is a plan view of the mechanism shown in Figure 2.

Figure 5 is a section on the line 5—5 of Figure 4.

30 Figure 6 is a front elevation of a machine to which our device has been applied combined with a piping and wiring diagram of the hydraulic and electrical layout.

Figure 7 is a front sectional elevation of the 35 footstock operating lever.

Figure 7A is a plan view showing the footstock partly in section and the lever for actuating same.

Figure 8 is a front elevation partly broken away 40 to show the ratchet and switch operating mechanisms for initiating operation of the dressing device.

In the drawings numeral 10 indicates the bed of a grinding machine; 11, a grinding wheel support slidably mounted thereon; and 12, a grinding wheel rotatably mounted in said support. A work carriage 100 has been mounted thereon, a headstock 101, and a footstock 102, a work piece 11, in this case a camshaft is mounted between said headstock and said footstock in the usual manner.

In Figure 1 is shown a mechanism for effecting a feeding movement of the grinding wheel comprising a hand wheel 13 mounted on a hand wheel shaft 14, said hand wheel shaft having a 55 bevel gear 15 meshing with another bevel gear 16 on a vertical shaft 17. Said vertical shaft is connected to a feed screw 18 thru gearing not shown. Said hand wheel and associated parts may be rotated intermittently by means of a 60 ratchet wheel 19 actuated by a pawl 19'. Said

pawl is mounted intermediate the ends of an elongated piston 20. The ends of said piston are slidably supported in two cylinders 21 and 22. The means for directing fluid under pressure to the cylinders will be described later.

Figure 1 also shows mounted on a wheel fender 23, a mechanism for dressing the grinding wheel. As shown in Figures 2—5, inclusive, this mechanism consists of a base 24 attached to a portion of the wheel fender. Said base has a dovetail 10 guide formed therein to receive the slide portion of a carriage 25. At the end of said base is attached a cylinder 26, having suitable fluid connections 27 and 28. A piston 29 in said cylinder is connected to carriage 25 thru piston rod 30.

The means for feeding diamond 31 comprises a holder 32 slidably mounted in a cylinder 33 which is integral with carriage 25. One end of said holder is bored out to receive a threaded bushing 34. A screw 35 is inserted in said bore 20 in threaded engagement with said bushing. A screw adjusting mechanism is attached to said carriage and consists of a plate 36 in which are formed cylinders 37 and 38 for receiving a piston 39 and cylinders 40 and 41 for receiving piston 42. Said cylinders are arranged in parallel relation in said plate. Said screw 35 has an unthreaded portion extending thru plate 36, and having a bearing 43 therein. The said plate is recessed where the end of screw 35 emerges and a ratchet wheel 44 keyed to the unthreaded portion of screw 35 is inserted therein. Said ratchet wheel may be actuated by pistons 39 and 42 thru pawls 45 and 46, respectively, mounted in slots 47 and 48 in said pistons and urged into engagement with said ratchet by springs 49 and 50. A hand wheel 51 keyed to the screw shaft provides means for manually actuating the screw 35. The amount of feed at each stroke of the various feed pistons may be adjusted by means of stop screws 55, 56 and 57.

A limit switch 52 mounted on fender 12 is depressed at the end of a dressing stroke in one direction by a cam 53. Said cam is attached to an arm 54 which is in turn secured to plate 36.

The mechanism for initiating operation of the dressing mechanism consists of a footstock lever 60, Figure 7, and a normally closed switch 63, the function of which is to deenergize a solenoid 64 when said lever is moved to withdraw the footstock center from a work piece. When said lever is shifted it may be latched in the new position by means of a key 110, which engages a slot 111 in a disk 112. Said disk is mounted on a stud 113 about which lever 60 is also mounted. Key 110 is formed on the end of a lever 114 pivoted at 115 to lever 60 and conforming in shape to said lever 60. A spring 116 urges key 110 into contact with disk 112. A pin 117 is slidably inserted in the handle 118 of lever 60. One end 60

of said pin engages lever 114, the other end protrudes from the top of handle 118. Depressing said pin withdraws key 110 from notch 111 and permits return of lever 60 to normal position.

5 Solenoid 64, Figures 6 and 8, is operatively connected to a ratchet mechanism the function of which is to operate a switch 66 at predetermined intervals. Said mechanism consists of a ratchet wheel 120 rotatably mounted on a stud 121, which 10 in turn is mounted on a panel 122, on which are mounted also the switch 66 and solenoid 64. A switch operating mechanism is attached to ratchet 120 and consists of a disk 67 having mounted on its periphery a series of removable 15 spaced studs 67'. A segmental cam 65 is loosely mounted on stud 121. Said cam carries a pawl 123 pivotally mounted thereon and urged into contact with the teeth of ratchet 120 by a spring 123'. Another spring 124, one end of which is 20 attached to said cam and the other end to panel 122, serves to reset the cam and pawl after each impulse. A stationary pin 130 limits the reset movement of cam 65. A spring 125 attached to 25 said panel engages said ratchet wheel and acts as a detent to prevent backward movement of said ratchet. Solenoid 64 is attached to said segmental cam by a link 126 pivotally attached thereto by a stud 127. An extension 128 of said link is shaped to conform to the periphery of 30 ratchet wheel 120 and is moved into contact therewith as cam 65 is rotated by solenoid 64. Said extension acts to lock said ratchet at this point and prevents an overrun thereof.

An operating arm 132 on switch 66 carries a 35 roller 131 normally in engagement with the periphery of disk 67 or studs 67'. When said roller is in contact with the periphery of said disk a circuit is closed thru said switch to energize solenoid 68. When said roller engages one of 40 the studs 67', the circuit thru switch 66 is held open. A smaller roller not shown is mounted on the same stud as roller 131 in position to be engaged by cam 65 on its working stroke to lift said roller 131 out of contact with said disk or 45 said studs and open the circuit thru switch 66.

Operation

When the operator pulls footstock lever 60 to 50 release a work piece 61, a latch holds it in release position. A button 62 on said lever engages switch 63 and opens the circuit to deenergize solenoid 64. When the solenoid is deenergized cam 65 is reset by a spring 124. Resetting cam 65 permits the roller on switch 66 to move toward 55 normal position. If one of the studs 67' is in the way the switch will not close and the dressing operation will not take place. If disk 67 carrying studs 67' is moved to a position where, upon resetting cam 65 the roller drops between the studs, 60 then the circuit will be closed thru switch 66 to energize solenoid 68 and relay 78.

Closing switch 66 energizes the coil of relay 78 65 to open the circuit which it controls so that footstock lever may be released and switch 63 closed without again energizing solenoid 64. Fluid under pressure for operating the dressing mechanism and the wheel feed mechanism may be supplied by any suitable means thru line 69 to valve 70. Said valve may be actuated in one direction 70 by solenoid 68 and in the other direction by a spring 71. When solenoid 68 is energized as above described valve 70 is shifted to direct fluid under pressure from line 69 thru line 72 from which said fluid is distributed to cylinder 21 to 75 effect a feeding movement of the wheel equal to

the amount to be removed therefrom in dressing plus the amount of wear on the wheel. Said fluid passes on to cylinders 37 and 40 where pawl 45 effects a feeding movement of the diamond somewhat less in magnitude than the above mentioned wheel feed movement. Said fluid in cylinder 40 effects a resetting movement of piston 42 and pawl 46. From line 72 fluid pressure passes thru line 74, throttle valve 74' and check valve 75 to the head end of piston 29. The flow 10 of fluid thru said check valve is unrestricted so that piston 29 traverses the diamond 31 across the surface of the grinding wheel at a comparatively high speed. Said high speed may be varied by an adjustable throttle valve 74' in line 74. 15 During this traversing movement the cam 53 opens contacts 76 and closes a circuit across contacts 77.

Solenoid 64 is energized when the circuit is closed thru 77 and the pawl 123 is actuated to 20 rotate disk 67 a predetermined amount. A portion of cam 65 engages the roller of switch 66 and opens the circuit at this point to deenergize solenoid 68 and relay 78. Deenergizing relay 78 permits the circuit to the footstock switch to be 25 closed. Deenergizing solenoid 68 permits shifting of valve 70 to reverse position whereupon pawl 46 actuated by piston 42 gives the diamond an additional feeding movement while pawl 45 is reset. Pawl 19' for actuating the wheel feed is also 30 reset at this time. An unrestricted supply of 35 fluid under pressure is directed thru line 73 and 27 to the rod end of piston 29 to traverse the diamond back to starting position. The exhaust from said piston must pass thru throttle valve 79 since check valve 75 is closed to fluid moving in that direction. Throttle valve 79 may be set to permit any desired speed on the return stroke. On the return stroke of the dresser, switch 52 40 returns to normal position. The circuit to solenoid 64 is deenergized and the pawl returned to 45 normal position.

Releasing the footstock lever closes switch 63 and thus energizes solenoid 64 to give the disk 45 67 another incremental movement.

Extreme accuracy in size may be maintained by compensating for diamond wear as slight variation in work size occurs. Assuming that the dressing tool is not subject to wear, the feeding 50 of the wheel to compensate for the reduction in diameter thereof by wear and dressing should be effective to maintain a given size of work indefinitely. However, because the dressing tool is subject to wear, the finished size of the work 55 may vary in direct relation to the wear on said tool. Applicant's method of compensating for this wear consists in setting the dressing tool so that the grinding wheel grinds to the oversize limit when the wheelbase reaches its forward 60 limit of movement. As the dressing tool wears away the work size will approach the undersize limit. The dressing operation is initiated upon removal of the work from the machine. Therefore, by gauging the work before removing same 65 from the machine, the operator may determine whether the diamond should be reset and how much. In this way, any inaccuracy in work size due to diamond wear may be corrected before the wheel is dressed for another grinding operation. 70

We claim:

1. In a device of the kind described a work support, a footstock mounted thereon, a spindle in said footstock, means for operating said spindle, a wheel support, a grinding wheel rotatably

- mounted thereon, a wheel dressing tool and means responsive to operation of said spindle operating means for initiating a dressing operation on said wheel.
5. 2. In a device of the kind described, a wheel support having a grinding wheel rotatably mounted thereon, a dressing tool, mechanisms for effecting relative feeding and traversing movements between said dressing tool and said 10 grinding wheel, means for feeding said wheel thru a distance equal to the amount to be removed by dressing plus the wear on the wheel, means for feeding said dressing tool thru a part of said distance before the traverse movement begins and thru the remainder of said distance before the return stroke of said traverse movement.
15. 3. In a device of the kind described, a wheel support, a grinding wheel mounted thereon, a dressing tool therefor, fluid operated means for effecting a relative traversing movement between said wheel and said dressing tool, a solenoid operated valve for controlling said reciprocating mechanism, a normally closed circuit for energizing said solenoid, a second solenoid adapted 20 when energized to open said normally closed circuit, a normally closed circuit for said second solenoid, a second circuit for said second solenoid, and means responsive to said traversing movement for opening said first circuit and closing said second circuit.
30. 4. In a grinding machine, a work support, a spindle mounted therein for rotatably supporting a work piece, a wheel support having a grinding wheel rotatably mounted thereon, means for effecting a feeding movement of said wheel support, a dressing tool movable with said wheel support, means for feeding said dressing tool toward said wheel and means for effecting a joint operation of said spindle with said wheel feeding means and said wheel dressing means.
40. 5. A grinding machine having a work carriage and a wheel support, means for rotatably supporting a work piece on said carriage including a footstock, means whereby said footstock may be operated to load and unload work pieces, a wheel dressing device and means actuated upon operation of said footstock for effecting operation of said dressing device.
45. 6. In a device of the kind described, a wheel support having a grinding wheel rotatably mounted thereon, a dressing tool, mechanisms for effecting relative feeding and traversing movements between said dressing tool and said grinding wheel, means for feeding said wheel thru a distance equal to the amount to be removed by dressing plus the wear on the wheel, means for feeding said dressing tool thru a part of said distance before the traverse movement begins and thru the remainder of said distance before the return stroke of said traverse movement and means for effecting said return stroke at a different rate than the initial stroke.
55. 7. In a device of the kind described, a work support, a footstock mounted thereon, a spindle in said footstock, means for operating said spindle, a wheel support, a grinding wheel rotatably mounted thereon, a wheel dressing tool, means for effecting a traversing movement of said tool including a reversing mechanism, means for shifting said reversing mechanism, a switch for actuating said shifting means, a ratchet mecha-
- nism for operating said switch and means responsive to operation of said spindle operating means for actuating said ratchet mechanism.
8. A device of the kind described comprising a dressing tool, fluid pressure means for effecting a traversing movement of said tool, a valve for reversing said traversing movement, means for shifting said valve, a switch for actuating said shifting means, a ratchet mechanism for operating said switch including a pawl and ratchet and means for actuating same, said actuating means including means for limiting the movement of said ratchet.
10. 9. In a device of the kind described, a work support, a footstock mounted thereon, a spindle in said footstock, means for operating said spindle, a wheel support, a grinding wheel rotatably mounted thereon, a wheel dressing tool, means for effecting a traversing movement of said tool including a reversing mechanism, means for shifting said reversing mechanism, a switch for actuating said shifting means, a ratchet mechanism for operating said switch, means responsive to operation of said spindle operating means for actuating said ratchet mechanism and means for determining the frequency of operation of said dressing tool.
15. 10. A device of the kind described comprising a dressing tool, fluid pressure means for effecting a traversing movement of said tool, a valve for reversing said traversing movement, means for shifting said valve, a switch for actuating said shifting means, a ratchet mechanism for operating said switch including a pawl and ratchet, means for actuating same, said actuating means including means for limiting the movement of said ratchet and means movable with said ratchet for determining the frequency of operation of said dressing tool.
20. 11. In a machine of the kind described, a wheel support having a grinding wheel rotatably mounted thereon, a wheel dressing tool, means for providing a relative reciprocating movement between said dressing tool and said wheel including a motor, means for causing said motor to effect said movement in one direction at a given speed, including a throttle valve set for a comparatively high speed, a reversing mechanism for reversing said movement, and speed control means operable upon initiation of movement in the opposite direction for changing said speed including a second throttle valve set for a comparatively slow speed, and means for bypassing said second valve during movement of said carriage in one direction.
25. 12. A grinding machine having a grinding wheel, a dressing tool therefor, means for effecting a relative traversing movement between said wheel and said dressing tool, a reversing mechanism for determining the direction of said traversing movement, means including an electromagnet and means for energizing same for actuating said reversing mechanism to cause said movement in one direction, means responsive to said traverse movement for de-energizing said electromagnet, and resilient means for thereafter actuating said reversing mechanism to cause said movement in the opposite direction.
